(57) **CLAIM**

The ornamental design for a bottle, as shown and described.

DESCRIPTION

FIG. 1 is a top front perspective view of a bottle showing my new design;

FIG. 2 is a top plan view thereof;

FIG. 3 is a bottom plan view thereof;

FIG. 4 is a right side elevational view thereof;

FIG. 5 is a front elevational view thereof;

FIG. 6 is a left side elevational view thereof; and,

FIG. 7 is a rear elevational view thereof.

The dot-dot-dash-dot-dot-dash broken lines shown in the drawings are for environmental purposes only and form no part of the claimed design.

The dot-dot-dot-dot-dot broken lines shown in the drawings define the boundary of the claim and form no part of the claimed design.
